UNITED STATES PATENT OFFICE.

JAMES P. FREEMAN, OF CHICAGO, ILLINOIS, ASSIGNOR TO SAMUEL M. BRYAN, OF WASHINGTON, DISTRICT OF COLUMBIA.

ARRESTER FOR ELECTRIC CURRENTS.

SPECIFICATION forming part of Letters Patent No. 367,901, dated August 9, 1887.

Application filed January 6, 1887. Serial No. 223,589. (No model.)

To all whom it may concern:

Be it known that I, JAMES P. FREEMAN, a citizen of the United States, and a resident of Chicago, in the county of Cook and State of Illinois, have invented certain new and useful Improvements in Arresters for Electric Currents, of which the following is a specification.

My invention relates to that class of electric-current-arresting devices intended to relieve the main line of the effects of being suddenly overcharged with a heavy current, and to prevent the injurious results of conducting such currents along a line not adapted to carry them; and my invention consists in a device constructed and arranged substantially as set forth hereinafter.

In the accompanying drawings, Figure 1 is a perspective view illustrating my improved device for arresting electric currents. Fig. 2 is a perspective view illustrating a modification. Fig. 3 is a longitudinal cross section of the same.

An electro-magnet, A, consists of a bobbin of magnetic material, having heads 2 4, around which bobbin is coiled an insulated wire connected at one end to the section 3 of the main line and at the opposite end to the head 4, in electrical contact with a bracket, 5, preferably forming a part of said head, within which is pivoted an arm, 6, constituting a movable armature. The head 2 of the bobbin carries an insulated block, 7, which extends below said head and is connected by a conductor, 8, with the ground, and extending in front of said head 2, and insulated therefrom, is a bracket, 9, with which is connected the other section, 10, of the main or telephone line, and which has an arm extending beneath the free end of the arm 6, and provided with a set-screw, 12, upon which the arm 6 rests when at the limit of its lowest motion. An insulated and perforated bracket, 13, is connected with the head 4 of the bobbin, and serves as a means of securing the lightning-arrester to any suitable support, with the pivoted armature 6 in a horizontal position below the bobbin. So long as the line is in its normal condition there is a continuous electrical circuit from the section 3, the bobbin-wire metallic head 4, bracket 5, armature 6, set-screw 12, and bracket 9 to the other section, 10,

of the telephone-wire; but should this condition be disturbed by an excessive current upon the main line 3 10, the bobbin becomes magnetized and the pivoted armature 6 is attracted toward the edge of the head 2, breaking the circuit through the bracket 9, but making another circuit by contact with the block 7, through said block and conductor 8, to the ground.

The device thus constructed is wholly automatic in its action, and it results in an instant ground connection upon the main line being unduly charged, and an immediate breaking of the ground connection as soon as the main line is relieved of its excessive current, while when the parts are in their normal condition there is no undue resistance upon the main line. Where there is danger of the main line 3 10 being brought in contact with the conductors of electric-lighting systems, it is desirable to prevent the passage of a current from said conductors through the electro-magnet A in case of such contact. For this purpose I modify the contacts with the movable armature, so as to short-circuit said current and prevent such a constant flow.

The modified construction for this purpose is illustrated in Fig. 2, in which the bracket 13, of conducting material, connected to, but insulated from, the bracket 9, carries set-screw 15, making contact with an arm, 16, constituting a prolongation of the armature 6 on the opposite side of the pivot. In this case the main-line wire 3 is electrically connected with the bracket 13 and with one end of the spool-wire at x, the opposite end of said wire being connected with the metallic head 4 and bracket 5, the other connections being the same as in the first instance. When the resisting device, constructed as shown in Fig. 2, is in its normal condition, the circuit is through the line-wire 3, electro-magnet, armature 6, set-screw 12, and line-wire 10; but when the bobbin is magnetized and the armature is drawn against the block 7 and set-screw 15, breaking contact with set-screw 12, the main-line current, instead of going to ground through the armature 6, block 7, and conductor 8, is short-circuited through the bracket 13, set-screw 15, and armature 6 to the block 7, so that the bobbin and coil are practically cut out of the line during the time

of the passage of the excessive current, however long the same may last.

By making the bobbin magnetic and including it in the line-circuit I produce a very simple, cheap, and effective arrangement that is delicate in operation and not liable to get out of order. The bobbin being magnetic, there is no necessity of a separate core, and the wire of the coil being wound immediately upon the bobbin the full magnetic effect of the currents passing through the coil is obtained, so that the device is operative under comparatively slight changes in the current, and by connecting the armature directly to the magnetic bobbin the construction is simplified and the device made compact.

The arrangement of the above-described parts may be varied according to circumstances, the form of the electro-magnet being altered and the contacts differently arranged, without departing from the main feature of my invention, whereby the electro-magnet is magnetized by the extra current to attract a movable armature, and thereby automatically change the line of conduction.

The above-described device is adapted for use upon any lines liable to be overcharged, but is especially applicable in connection with telephone-lines and with systems in which underground cables are employed and in lines which are liable to contact with heavily-charged electric-lighting conductors.

Without limiting myself to the precise construction and arrangement of parts shown, I claim—

1. The combination of the electro-magnet A, having its coil and its metallic bobbin connected with one section of the main line, an armature pivoted below the electro-magnet and connected with the spool at its pivoted end, an insulated block, 7, connected with the ground and secured to the magnet in a position

above the free end of the armature, and an insulated bracket connected with the other section of the main line and provided with a set-screw 45 below the free end of the armature, all substantially as set forth.

2. The combination of an electro-magnet having its coil connected with the bobbin and with one section of the main line, and a movable armature normally in connection with the other section of the main line, an insulated block in connection with the ground, and an insulated contact-piece in constant electrical connection with the first section of the main line and arranged in position to make contact with the movable armature when the latter makes contact with the said block, substantially as set forth.

3. The combination of the electro-magnet, 60 main-line conductor 3, connected with the coil of the magnet and with the bracket 13, supporting a set-screw, 15, a pivoted armature extending over the set-screw 15, an insulated bracket supporting a set-screw, 12, and connected with the other section of the main line, and an insulated block, 7, connected with the ground and arranged above the free end of the armature, substantially as set forth.

4. An electric cut-out composed of a magnetic bobbin and a coil thereon, a conducting-lever normally in the circuit connected to one head of the bobbin and an insulated ground connection upon the other head, and a bracket attached to said head and included in the main-line circuit, with which bracket the lever normally contacts, substantially as described.

In testimony whereof I have signed my name to this specification in the presence of two subscribing witnesses.

JAMES P. FREEMAN.
